ELECTRIC TOOTHBRUSH

Nathan K. Morris and Elias Saka, both of 4th and Railroad Aves., Neptune City, N.J.

Filed June 4, 1963, Ser. No. 75,206

Term of patent 14 years

(Cl. D9—2)

FIGURE 1 is a side elevational view of an electric toothbrush embodying our new design;

FIGURE 2 is a perspective view of the electric toothbrush shown in FIGURE 1, with the brush element removed;

FIGURE 3 is a top plan view of the toothbrush shown in FIGURE 2; and

FIGURE 4 is a bottom plan view of the toothbrush shown in FIGURE 1.

We claim:

The ornamental design for an electric toothbrush, as shown.
